CLAIM

The ornamental design for a garment with magnetic clasp as shown and described.

DESCRIPTION

FIG. 1 is a perspective view of a first embodiment of a garment with magnetic clasp showing my new design;

FIG. 2 is a front view thereof;

FIG. 3 is a back view thereof;

FIG. 4 is a right side thereof;

FIG. 5 is a left sideview of thereof;

FIG. 6 is a top plan view thereof;

FIG. 7 is a bottom plan view thereof; and

FIG. 8 is a cross-sectional view of the garment with magnetic clasp of FIG. 2.

FIG. 9 is a perspective view of a second embodiment of a garment with magnetic clasp showing my new design;

FIG. 10 is a front view thereof;

FIG. 11 is a back view thereof;

FIG. 12 is a right side view thereof;

FIG. 13 is a left side view thereof;

FIG. 14 is a top plan view thereof;

FIG. 15 is a bottom plan view thereof; and

FIG. 16 is a cross-sectional of the garment with magnetic clasp of FIG. 10.

FIG. 17 is a perspective view of a third embodiment of a garment with magnetic clasp showing my new design;

FIG. 18 is an elevation anterior view thereof;

FIG. 19 is an elevation posterior view thereof;

FIG. 20 is a right side view thereof;

FIG. 21 is a left side elevation view thereof;

FIG. 22 is a top plan view thereof;

FIG. 23 is a bottom plan view thereof; and,

(Continued)

FIG. 24 is a cross-sectional view of a the garment with magnetic clasp of FIG. 18. The evenly spaced broken lines shown in FIGS. 1-24 are for the purpose of illustrating portions of the garment with magnetic clasp that form no part of the claimed design. The unevenly spaced broken lines within FIGS. 2, 10, and 18 depict enlarged detail views of the garment with magnetic clasp which form no part of the claimed design.
